(57) **CLAIM**

The ornamental design for a surge protector, as shown and described.

DESCRIPTION

FIG. 1 is a top perspective view of a surge protector;

FIG. 2 is a bottom perspective view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front elevational view thereof; and,

FIG. 8 is a back elevational view thereof.

The dash-dash broken lines shown in the drawing figures depict portions of the surge protector that form no part of the claimed design. The surge protector is shown with dot-dot-dash broken lines indicating a symbolic break in its length. The appearance of any portion of the article between the dot-dot-dash broken lines forms no part of the claimed design.
